UNITED STATES PATENT OFFICE

2,656,555

MACHINE FOR SIMULTANEOUSLY CONDITIONING THE ATTACHING SURFACE AND TRIMMING THE EDGE OF UNATTACHED SHOE SOLES

John H. Kelly, Pittsburgh, Pa.

Application January 8, 1951, Serial No. 204,881

7 Claims. (Cl. 12—85.1)

1

This invention relates generally to machines for conditioning the soles of footwear and more particularly to machines for automatically and simultaneously conditioning the edges and the cementing face of the soles of footwear.

This invention is an improvement on the invention disclosed in United States Patent 2,545,471, entitled Shoe Sole Conditioning Machine, issued March 20, 1951.

This machine is made to operate on unattached shoe soles. In the preparation of outer soles intended to be attached to certain types of shoes with adhesive cement, it is now customary to rough the attaching face of the sole and trim or bevel the sole edge before that sole is attached to the bottom of a lasted shoe. These are two independent operations which necessitate double handling of the sole.

The edge trimming operation is now practiced by holding a single shoe sole in the hands and revolving its perimeter against a rotary edge trimming cutter which invariably leaves tool marks on the soles at the start and stop points and is a time-consuming operation in the hands of the most skilled workmen.

It is the purpose of this invention to combine the trimming operation with the roughing operation into a single operation in passing a sole through the machine.

In the manufacture of certain types of shoes it is the practice of the trade to cut the sole with a die that is accurately made to fit the shoe to which it will be subsequently attached. Very little stock, if any, is allowed for removal by the edge trimming operation. The purpose of the edge trimming operation is to bevel the corners of the sole edge or to shape the edge with various designs that impart a finished appearance to the edge. The desired shape or profile of the sole edge is formed on the trimming tool and is transferred to the sole edge as the sole is guided and fed into the path of the tool.

In order to produce a smooth well defined edge without sacrificing the quality of the roughened cement track it is necessary that the speed of the work be timed or correlated to the speed of the roughing tool and also the trimming tool.

On certain types of material such as rubber soles the cutting tool consists of a grinding wheel, whereas when operating on leather soles, it is preferable to use a fluted edge trimming cutter.

It may on occasions be desirable to rough the sole without trimming the edge. In this event the grinding wheel is not rotated under power and merely acts as a guide roll. On the other

2

hand it may be necessary to perform the trimming operation without roughing the surface of the sole. The cutting tool is then replaced with a feed roll which consists of a cylindrical member having a plurality of continuous thread-like helices cut on its diametrical face. The thread transmits lateral thrust to the sole so that it is kept in constant contact with the edge trimming tool which shapes the edge of the sole.

Another object of this invention is the provision of an improved machine that aids in automatically feeding and guiding unattached soles of footwear while their surfaces are being conditioned preparatory to the application of an adhesive for attaching the same to footwear.

Another object is the provision of a conditioning machine for the soles of footwear which will simultaneously trim the perimetral edge of the sole, the edge being profiled or shaped, while the attaching surface is roughened. The machine profiles the edge of the soles and simultaneously rands or otherwise conditions a band adjacent the perimetral edge of the sole.

Another object is the provision of a sole conditioning throat formed by subjacently mounted pressure roll and cutter rolls, a laterally disposed feed roll and a guide roll, all of which are power driven and operate directly on the sole to automatically condition the same. The sole is pressed against the cutter by the pressure roll, and the feed roll aids in urging the edge of the sole through the throat and against the guide roll which may be provided with tool surfaces such as a stone, a cutter, or combined cutter skiver to shape and profile the edge of the sole as it passes from the throat. The feed roll is closely adjacent the ends of the cutter and pressure rolls and has a roughened or knurled surface which drives the edge of the sole at the same peripheral speed as the pressure roll and in the same direction. The teeth of the cutter follow a threadlike pattern and produce a thrust on the sole driving it toward the feed roll. The cutter rotates to move the sole in the same direction but at a much faster surface speed than the pressure roll. The guide or trimming roll is driven against the movement of the sole when skiving or profiling the sole edge but may be an idling roll when functioning only as a guide roll. Thus it is the position of the guide roll in front of the cutter and pressure roll that determines its guiding ability and it is adjustable across the front of the conditioning throat to provide the best guiding location for different shaped soles. The adjustment of the guide roll to profile and

guide different sole patterns simultaneously is another important object of this invention.

Other objects and advantages appear herein-after in the following description and claims.

The accompanying drawings show, for the purpose of exemplification without limiting the invention of claims thereto, certain practical embodiments of the invention wherein:

Fig. 1 is a plan view of the machine comprising this invention with the edge trimming beam and motor removed.

Fig. 2 is a view in side elevation with parts broken away of the machine as shown in Fig. 1.

Fig. 3 is a sectional view showing the sole conditioning throat taken along the line 3—3 of Fig. 2.

Fig. 4 is a sectional view taken along the line 4—4 of Fig. 2.

Fig. 5 is a plan view of the feed roll drive which is mounted on the machine as a separate unit.

Fig. 6 is a side elevation of the structure shown in Fig. 5.

Fig. 7 is a view in side elevation showing a combination edge trimming and chamfering cutter.

Referring to the drawings the shoe sole conditioning machine is mounted on the base 1 which is constructed on a standard and contains a motor and a blower unit together with a conduit system for cooling the cutter mechanism and for withdrawing the cuttings from the vicinity of the conditioning operation. The motor employed to drive the conditioning machine may be of ordinary induction type or one may provide a variable speed motor for this use to obtain different sole conditioning effects. The motor drives the shaft 2 through the V-belt 3 on the pulley 4. The shaft 2 extends through and is journaled in a speed reducing mechanism 5 of any suitable design. The forward end of the shaft 2 extends through the bearing 6 in the back wall of the machine casting and into the cutting chamber 7 the top of which is closed by the table member 8. The table 8 is pivotally supported as indicated at 9 to swing outwardly and open the upper end of the chamber 7.

A cutter 10 is mounted on the end of the shaft 2 and is held in place by the left-hand thread screw 11 which clamps the cutter against a shoulder on the shaft which may be under the pressure of a pressure washer or spacer member as shown. The cutter rotates in a clockwise direction as viewed in Fig. 2 and is preferably of a design such as disclosed in Patent No. 2,429,822 with the interrupting teeth following the left-hand helix. The cutter may be of any desirable width according to the width of the surface to be conditioned on the shoe sole. The cutter is formed so that it may be turned end for end on the shaft and the teeth are provided with the duplicate cutting profiles to increase its life. This cutter roll 10 is preferably made with tungsten carbide tips or other suitable hard metal to give a lasting quality and relative long life in service in cutting soles of leather, rubber or other synthetic material.

It will be noted that the ridges of the teeth of the cutter extend slightly above the surface of the table. The pivotal support of the table is adjustable to regulate the height of the same to maintain the height of the sole surface relative to the cutter.

The chamber 7 terminates in a downwardly and rearwardly open passage that may be connected by a flexible hose, such as indicated at 12, which proceeds to the blower and thence to a

suitable discharge system. The air being drawn by the blower through the passage 12 will pick up and convey any of the material that is removed from the soles by the cutter and draw or suck the same into the pneumatic system. This influx of air also functions to cool the tools and the bearings which materially increases the life of the machine.

The speed reducer 5 is also provided with a shaft 13 which extends out the front end and is provided with a spur gear 14 that meshes with the spur gear 15 on the shaft 16. The shaft 16 is journaled in a casting 17 which is pivotally supported on the shaft 13 and has a rearwardly extending arm 18.

The forward end of the shaft 16 is constructed to receive the pressure roller sleeve 20 which is held in place by the nut 21. The pressure roller is a resilient sleeve preferably made of rubber or some similar plastic material and is made to rotate in a counterclockwise direction. A throat is formed between the pressure roll and the cutter, which is immediately below and in line with the pressure roll. The cutter and the pressure roll rotate in opposite directions to move a sole through the throat which is indicated at 22.

The casting 17 with its rearwardly extending arm 18 is provided with an actuating rod 23 which is secured to the end of the arm and extends downwardly being connected to a rocking lever actuated by a foot pedal not shown. The rocking casting 17 is provided with a stop member 24 that is part of the plate 30 and the casting 17 may be adjusted by the nut 25 supported on the rod 23. The rocking casting 17 is provided with a spring member 27 that engages an adjustable screw member 28 for the purpose of determining the pressure applied through the pressure roll against the sole. The screw 28 may be calibrated so that the pressure exerted at the throat 22 is in accordance with the iron measurement of the sole to obtain a predetermined roughened condition.

The table 8 is removably supported on the post 26. The plate member 30, as shown in Figs. 5 and 6, is mounted on the machine casting and carries a train of gears, the train starting with the beveled pinion 31, the spur gear 32, the intermediate idler spur gears 33 and 34, and the final gear 35 which is integral with the feed roll 36 that is provided with a knurled surface. This whole train of gears is independently mounted on the plate 30 and it is separably removable from the machine casting by the screw members such as indicated at 37. The beveled pinion 31 extends upwardly and engages the beveled gear 38 secured to the end of the shaft 13 as shown in Fig. 4. The bearings 40, shown in Figs. 1 and 4, support the rocking casting 17 on the shaft 13. The peripheral speed of the small feed roll 36 is the same as the speed of the perimetral surface of the pressure roll 20 which accounts for the necessity of the train of gears, namely to increase the speed of the feed roll so that the surface feed is the same as that of the pressure roll.

The base is provided with an upstanding column 41 arranged to receive the split clamp casting 42 that is clamped in place by the clamping and locking bar member 43 for the purpose of supporting the edge trimming machine 44 relative to the throat 22. The casting 42 carries the motor 45 which has the drive pulley 46, driving the V-belt 47 and the driven pulley 48 on the spindle 49 that has attached thereto the profiling or edge trimming tool member 50, that is

5

adjustable in an arc in front of the throat 22 formed between the cutter and the feed pressure roll.

The spindle 49 is housed in spaced bearings 51 in the fore end of the casting 42. The driving connection is enclosed by the shell member 52 and held in place by the nut 53. As shown in Fig. 1 the tool member 50 may be swung from the position shown in full lines to the position shown in dotted lines between which positions the tool 50 may be adjusted for the purpose of automatically conditioning the soles of different size and shape. An adjustable stop 54 determines the limit that the tool 50 may be swung inwardly toward the plate 30.

As shown in Fig. 2 the tool 50 is made up of a grinding wheel 55 and two shield members 56, one on each side of the grinding wheel which encase the same and make the upper and lower edges of the grinding wheel ineffective as against any part of the machine or the sole being conditioned. As shown in Fig. 7 the tool 50 may be replaced by the tool 50' shaped as a cutter to put a beaded surface in the edge of the sole and also to skive the under surface of the sole. The tool 50' is provided with the cutter members 51 and the randing lip 58. Thus the tool 50' may be constructed of metal and have cutting edges when operating on leather, but when operating on rubber or synthetic material it is preferable to use a stone or similar abrading tool. As indicated in Fig. 1 the tool 50 rotates in a clockwise direction which is against the movement of the sole as it passes through the throat 22. This is the preferred rotation of the trimmer tool 50'. However it may be rotated in a counterclockwise direction and still trim the edge. Either direction of rotation of the trimming tool or an idling roll at this point provides the proper component of force to resist the movement of the shoe sole and guide it through the throat.

The sole is ordinarily started adjacent the shank and it is preferable, although not necessary, to depress the foot pedal and rock the casting 17 so as to raise the pressure roll and insert the sole in the throat 22 when the machine is in operation. As soon as the foot treadle is released and allows the rocking casting 17 to bring the pressure roll against the surface of the sole, the latter immediately becomes subject to the cutting and thrust action of the cutter 10 which forces the edge of the sole against the feed roll which in turn aids in moving the sole forward. Since the tool 50 is in front of the throat the sole engages the same and then is required to move laterally in a clockwise direction. The sole continues to travel in a circle and must be removed at the end or it will continue to travel.

The pressure roll and the cutter, with its helical teeth traveling in an annular path, operate on a sole which is traveling in a changing angular path due to its contact with the edge feed roll and engagement with the guide trimming roll which are the factors that cause the sole to automatically travel around its full perimeter. The thrust created by the cutter, and the angular position of the sole between its two edgewise contact points at the feed and the guide roll, produce a leverage which causes the sole to turn as it is driven forward. It is necessary that the edge of the sole keep in contact with the feed roll at all times which is accomplished by the lateral thrust of the cutter. Soles with abrupt turns such as narrow heels or toes have a tendency to leave the feed roll when the sole is piv-

6

otting too fast at the toe or heel. The rate of pivot speed can be controlled by increasing the lateral thrust. This may be accomplished by moving the trimming cutter outward from the roughing cutter on its adjustable arc to increase the gap between the sole edge contact points and thus increase the angle or lateral thrust of the sole. This added thrust will retard the sole at the pivot points and keep it in close contact with the feed roll. This may also be accomplished by increasing the spring tension on the pressure roll housing. It will exert pressure on the sole, causing the teeth of the roughing cutter to bite into the sole deeper and due to the teeth lying in a helical plane they will exert a greater lateral thrust and cause the sole to hug the feed roll.

In addition to making the sole constantly hug the feed roll, the amount of pressure exerted against the feed roll and trimming roll can be regulated by either of the above mentioned methods. It is the amount of pressure exerted against the trimming roll that determines the degree of trimming or tock removal and by using these two methods of obtaining lateral thrust, the amount of stock removal can be accurately regulated.

I claim:

1. A shoe sole conditioning machine, comprising a rotary cutter, a rotary pressure roll mounted to cooperate with the rotary cutter in forming a throat through which a sole passes while being conditioned, a rotary feed roll having substantially the same peripheral speed as the pressure roll and mounted with its perimetral face adjacent the ends of the cutter and the pressure roll on one side of the throat to engage the edge of a shoe sole in the throat and aid in feeding it therethrough, and a rotary edge trimming guide roll adjacent the end of the throat to engage the edge of the shoe sole to profile and trim the same while automatically guiding it through the conditioning throat.

2. A shoe sole conditioning machine, comprising a rotary cutter, a rotary pressure roll mounted to cooperate with the rotary cutter in forming a throat through which a sole passes while being conditioned, a rotary feed roll having substantially the same peripheral speed as the pressure roll and mounted with its perimetral face adjacent the ends of the cutter and the pressure roll on one side of the throat to engage the edge of a shoe sole in the throat and aid in feeding it therethrough, a rotary edge trimming guide roll adjacent the end of the throat to engage the edge of the shoe sole to profile and trim the same while automatically guiding it through the conditioning throat, and power means to drive said edge trimming guide roll in a direction opposite to that of the movement of a shoe sole through the throat.

3. A shoe sole conditioning machine, comprising a rotary cutter, a rotary pressure roll mounted to cooperate with the rotary cutter in forming a throat through which a sole passes while being conditioned, a rotary feed roll having substantially the same peripheral speed as the pressure roll and mounted with its perimetral face adjacent the ends of the cutter and the pressure roll on one side of the throat to engage the edge of a shoe sole in the throat and aid in feeding it therethrough, a rotary edge trimming guide roll adjacent the end of the throat to engage the edge of the shoe sole to profile and trim the same while automatically guiding it through the condi-

tioning throat, and independent power means to drive said edge trimming guide roll in a direction opposite to that of the movement of a shoe sole through the throat.

4. A shoe sole conditioning machine, comprising a rotary cutter, a rotary pressure roll mounted to cooperate with the rotary cutter in forming a throat through which a sole passes while being conditioned, a rotary feed roll having substantially the same peripheral speed as the pressure roll and mounted with its perimetral face adjacent the ends of the cutter and the pressure roll on one side of the throat to engage the edge of a shoe sole in the throat and aid in feeding it therethrough, a rotary guide roll spindle mounted to swing in an arc in front of the sole conditioning throat, power means to drive said spindle, an edge trimming guide roll mounted on the spindle adjacent the end of the throat to engage the edge of the shoe sole passing out of the throat, and means to lock the arcuate position of the guide roll to automatically guide a shoe sole of predetermined size.

5. A shoe sole conditioning machine, comprising a rotary cutter, a rotary pressure roll mounted to cooperate with the rotary cutter in forming a throat through which a sole passes while being conditioned, a rotary feed roll having substantially the same peripheral speed as the pressure roll and mounted with its perimetral edge adjacent the ends of the cutter and the pressure roll on one side of the throat to engage the edge of a shoe sole in the throat and aid in feeding it therethrough, and an independently driven rotary edge trimming and skiving tool adjacent the end of the throat to engage the edge of the shoe sole to profile and trim the same while automatically guiding it around its complete perimeter through the machine.

6. A four-point contact shoe sole conditioning

machine comprising a frame, a rotary cutter roll mounted on said frame, a rotary pressure roll mounted on said frame to co-operate with the rotary cutter roll and forming therewith a dual contacting throat through which the sole passes while being conditioned, a rotary feed roll mounted on the frame with its perimetral face adjacent the ends of the cutter and pressure rolls at one side of said throat to engage the sole edge and form a third contacting point, a roughened perimetral surface on the said roll, and a rotary edge trimming guide roll adjacent the end of the throat to engage the edge of the sole to profile and trim the same while automatically guiding it through the throat and form the fourth contacting point, means to drive three of said rolls in unison and means to drive one of said rolls independently, all of said rolls simultaneously engaging the sole in the throat to control its movement and the conditioning thereof.

7. The structure of claim 6 characterized in that three of said rolls contacting the sole move it in the same direction and said fourth roll contacting the sole rotates in a direction opposite to the movement of the sole.

JOHN H. KELLY.
